(57) **CLAIM**

The ornamental design for a vaginal drug delivery device, as shown and described.

DESCRIPTION

FIG. 1 is a top left perspective view of a vaginal drug delivery device showing the new design;

FIG. 2 is a top plan view thereof;

FIG. 3 is a bottom plan view thereof;

FIG. 4 is a left side elevation view thereof;

FIG. 5 is a front elevation view thereof; and,

FIG. 6 is a rear elevation view thereof.

The broken lines showing portions of a vaginal drug delivery device is included for the purpose of illustrating environmental structure and forms no part of the claimed design. The opposite side not shown is a mirror image of FIG. 4.
